UNITED STATES PATENT OFFICE.

JESSE B. HELLER, OF HADDON HEIGHTS, NEW JERSEY, ASSIGNOR TO GRIFFIN CHOKER
ASH TRAY, INC., OF PHILADELPHIA, PENNSYLVANIA, A CORPORATION OF DELA-
WARE.

CIGARETTE CHOKER.

Application filed September 16, 1921. Serial No. 501,099.

To all whom it may concern:

Be it known that I, JESSE B. HELLER, a citizen of the United States, residing at Haddon Heights, county of Camden, and State of New Jersey, have invented a new and useful Improvement in Cigarette Chokers, of which the following is a full, clear, and exact description, reference being had to the accompanying drawings, which 10 form a part of this specification.

This invention relates to an improvement in chokers for cigarettes, and is designed to provide an efficient device of this character combined with an ash tray which can 15 readily be pressed from glass, so the device can be sold at a nominal price.

Another object of my invention is to provide a device which can be readily washed so that it can be kept in a sanitary condition, 20 and thereby provide an article which may be kept in condition to be placed on dining tables, in cafes, etc.

The precise nature of my invention will be best understood by reference to the accompanying drawings which will now be described, it being premised, however, that various changes may be made in the general 25 form of the device without departing from the spirit and scope of my invention as defined in the appended claims.

Fig. 1 of the drawings is a plan view of one form of device made in accordance with my invention.

Fig. 2 is a sectional view on the line 2—2 35 of Fig. 1.

Fig. 3 is a view, similar to Fig. 1, showing a modified form.

Fig. 4 is a sectional view on the line 4—4 40 of Fig. 3.

In Figs. 1 and 2 of the drawings, I have shown a device having two inner arcuate shaped flanges *a* and an outer flange *b* extending upwardly from the base of the tray. The adjacent walls of the flanges *a* and *b* are 45 at an angle to a line perpendicular to the base so as to form tapered channels *c* between the flanges. These flanges extend along approximately 240° of the edge portion of the tray. Extending upwardly from the base of the tray at the edge thereof, between the ends of flange *b*, is a match holding portion *d* which extends above the flanges *a* and *b* and is provided with a cavity *e* for the reception of a package of the well known paper matches. *f* is a depres-

sion between the flanges *a* and the match holding portion *d* for the reception of ashes, etc. *g* is an opening in the inner wall of the match holding portion *d* and opens into the cavity *e* and the depression *f*. *h* is a similar 60 opening between the ends of the flanges *a*, which also opens into the depression *f* and the channel *c*. These openings *g* and *h* extend to the bottoms or near the bottoms of the cavity *e* and channel *c* respectively, and 65 are provided to permit wash water and dirt to pass from the cavity and channel. If desired, the flange *b* may be provided with a similar opening as indicated in dotted lines at *i*. 70

The width of the channel *c* at the bottom and for a portion of its height is less than the diameter of a cigarette, while the top thereof is slightly wider than the diameter of a cigarette. This will permit the ready 75 insertion of the lighted end of a cigarette, and by pressing the cigarette into the channel, the fire on the end of the cigarette will be choked.

The inner flanges *a* are provided with 80 cigar holding depressions *k*.

In Figs. 3 and 4, I have shown a structure provided with a single flange *l* which is provided with a plurality of cigarette choking cavities *m* of tapered form which are also in 85 communication with the ash receiving depression *f'* by means of openings *n*.

d' is a projection for holding a box of matches, which is also provided with a slot *e'* for the reception of a package of paper 90 matches.

As the cavities *m* are in communication with the depression *f'* through openings *n*, these cavities may readily be washed to maintain the article in a sanitary condition. 95

The advantages of my invention result from the provision of a combined cigarette choker and ash tray, which may be pressed in glass or other plastic material and in which the choker cavities are provided with 100 openings substantially the same height as the choker openings, through which dirt may be washed or swabbed.

Having now fully described my invention, what I claim and desire to protect by Letters Patent is:

1. A device of the character described having an ash receiving depression and a surrounding wall, there being a cigarette choking cavity in the wall, said cavity open- 110

ing upward at the top to receive the lighted end of a cigarette, said wall having a lateral opening communicating with both the ash receiving depression and the choking cavity and extending substantially the full depth of the latter from its cigarette receiving open top to its bottom.

2. A device of the character described having an ash receiving depression and a surrounding wall, there being a cigarette choking cavity in the wall opening upward to receive the lighted end of a cigarette, and having a bottom on about the level of the floor of the ash tray, there being a lateral opening of restricted width in the side wall of the cavity communicating with the ash receiving depression.

3. A device of the character described having an ash receiving depression, there being a cigarette choking cavity in the wall surrounding the depression, said cavity hav-

ing an open top and closed bottom, there also being a laterally extending opening affording communication between at least the lower end of said cavity and the depression.

4. A device of the character described having a central ash receiving depression, there being a conical cigarette choking cavity in the wall surrounding the depression, said cavity having open top and closed bottom, the axis of the cavity and the axis of the depression being substantially parallel to each other, there also being a laterally extending opening through the wall of the structure between said cavity and the depression extending substantially from the top to the bottom of the cavity.

In testimony of which invention, I have hereunto set my hand, at Philadelphia, Pa., on this 14th day of September, 1921.

JESSE B. HELLER.
